UNITED STATES PATENT OFFICE.

JOHN A. WADE, OF TRAVERSE CITY, MICHIGAN.

PROPELLER.

No. 848,942.

Specification of Letters Patent.

Patented April 2, 1907.

Application filed February 19, 1906. Serial No. 301,946.

To all whom it may concern:

Be it known that I, JOHN A. WADE, a citizen of the United States, residing at Traverse City, in the county of Grand Traverse and State of Michigan, have invented a new and useful Propeller, of which the following is a specification.

The principal object of the present invention is to provide a novel form of mechanism for propelling air-ships, carriages, and vehicles of all classes wherein atmospheric pressure may be successfully employed as the propelling medium.

A further object of the invention is to provide a device of this class in which a fan or similar member is arranged to create a partial vacuum in advance of a solid disk or similar member against which the pressure of the atmosphere may act for the purpose of moving the disk or other element and any vehicle by which said disk is carried.

A still further object of the invention is to provide a device of this class in which a cylinder open at both ends is provided with a revoluble fan having a solid center, which may form a part of and revolve with the fan or which may be stationary and supported by the cylinder, the fan serving to form a partial vacuum in advance of this solid central portion or disk and to force the air to the rear of the disk, so that the pressure of the displaced air plus atmospheric pressure may operate on said disk and advance the same.

With these and other objects in view, as will more fully hereinafter appear, the invention consists in certain novel features of construction and arrangement of parts hereinafter fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a sectional plan view of a propelling mechanism constructed in accordance with the invention. Fig. 2 is an end elevation of the same. Fig. 3 is a detail perspective view of the propelling-fan. Fig. 4 is a vertical section of a slightly-modified construction of propelling device.

Similar numerals of reference are em-

ployed to indicate corresponding parts throughout the several figures of the drawings.

The apparatus forming the subject of the present invention is designed principally as a means for propelling air-ships, boats, carriages, and vehicles of all classes, but which may also be employed to advantage as a stationary motor member for operating machinery of any type or employed for power purposes generally.

In carrying out the invention a cylinder 10, open at both ends, is placed on the vehicle to be propelled, and supported within the center of the cylinder in any suitable manner is a shaft 11, to which some motor element, such as that indicated at 12, is secured or connected.

Mounted on the shaft is a fan 15, having a solid central disk 16, which is about one-half as large in diameter as the cylinder 10. From the periphery of this disk project fan-blades 17, which may be set at any desired angle with respect to the longitudinal axis of the shaft and cylinder. The periphery of the fan is but slightly less in diameter than the bore of the cylinder, and when the shaft and fan are rotated the air will be drawn in at one end of the cylinder and forced out at the opposite end, resulting in a movement of the cylinder in the direction indicated by the arrow in Fig. 1.

During the operation of the fan a partial vacuum will be formed in advance of the disk 16, and this will naturally result in subjecting the rear face of the disk to the action of atmospheric pressure, the working force thus exercised in moving the disk in the direction indicated by the arrow being proportioned to the vacuum in advance of the disk, so that with a disk, say, six inches in diameter, and theoretically a perfect vacuum in advance of the disk, the atmospheric pressure acting on the rear face of the disk will be approximately four hundred and twenty-four pounds. It is of course impossible to produce a perfect vacuum in advance of the disk, so that the working pressure on the rear face would be less than that amount; but this working force is materially increased by the increase in pressure of the air at the rear of the disk due to the action of the fan. As the air in front of the disk is forced rearward there is more or less compression of air within the rear portion of the cylinder,

and this additional pressure plus atmospheric pressure constitutes the working force in moving the disk and the cylinder forward.

5. In order to increase the vacuum in advance of the disk, auxiliary cylinders 20 and auxiliary fans 21 may be employed, as shown in Fig. 1, and as the inlet end of the cylinder is of fixed area the application of a 10 number of fans will materially reduce the density of the air in advance of the fans and disks, and the working pressure of the atmosphere on the rear faces of the disks will thus be materially increased. The construction shown in Fig. 1 is, moreover, of considerable advantage, especially where used on air-ships or boats, in that by stopping one or other of the auxiliary fans the course of the vessel may be directed, these auxiliary fans 15 and cylinders being utilized as steering members. It is of course obvious that the solid disk 16 may form a part of the fan proper or may be in the form of a stationary member, this construction being illustrated in Fig. 4, 20 wherein a central disk 16' is shown as rigidly secured to the cylinder by arms 24, and said fixed disk is provided with a central bearing for the support of the operating-shaft 11. In this case also the air will be exhausted to a 25 greater or less extent at the inlet end of the cylinder, and atmospheric pressure plus the pressure of the air displaced will constitute the working force in advancing the disk and the cylinder.
30. With an apparatus constructed in accordance with this invention it is possible to utilize atmospheric pressure for power purposes to much better advantage than is the case with ordinary fans or helical propelling 35 devices which act as air-displacing members from their carrying-shafts to their peripheries.

I claim—

1. A propelling device for air-ships, carriages and the like, comprising a cylindrical 45 casing open at both ends and of substantially uniform diameter from end to end, a centrally-arranged disk within said casing, and means for exhausting the air in advance of the disk to permit the exercise of atmospheric pressure on the rear face of the disk, and the forward movement of the disk, the casing and the apparatus to which the latter is attached.
2. In a propelling device for air-ships, carriages and other vehicles, a casing open at both ends and of uniform diameter from end to end, a disk arranged centrally of the casing and adapted to be acted upon by atmospheric pressure to effect the forward movement, fan-blades arranged between the periphery of the disk and the wall of the casing, and means for operating the fan-blades to create a partial vacuum in front of the disk.
3. In apparatus of the class described, a 60 cylindrical casing open at both ends, and of substantially uniform diameter throughout its length, a revoluble fan arranged therein and having a solid central disk, the fan being arranged to create a partial vacuum in advance of the disk, auxiliary casings connected at their front ends to the main casing at a point in advance of the fan, and auxiliary fans mounted in auxiliary casings and acting to further exhaust the air in advance of the 70 main casing.

In testimony that I claim the foregoing as my own I have hereunto affixed my signature in the presence of two witnesses.

JOHN A. WADE.
